UNITED STATES PATENT OFFICE.

FRANK HUMPHREVILLE, OF LANCASTER, PENNSYLVANIA.

SHOE-POLISHING MACHINE.

No. 869,435.

Specification of Letters Patent.

Patented Oct. 29, 1907.

Application filed January 12, 1906. Serial No. 295,674.

To all whom it may concern:

Be it known that FRANK HUMPHREVILLE, a citizen of the United States, residing at Lancaster, in the county of Lancaster and State of Pennsylvania, has invented certain new and useful Improvements in Shoe-Polishing Machines; and he does hereby declare the following to be a full, clear, and exact description of the invention, such as will enable others skilled in the art to which it appertains to make and use the same.

10 The object of this invention is to provide a satisfactory shoe polishing machine adapted to operate conveniently on the shoes of several people successively or simultaneously in different seats or standing places. To this end, I employ a sliding gear driven by any convenient power, a flexible shaft rotated by said gear and sliding with it and a brush carried by said shaft, as well as certain co-operative parts and special details of construction, all as more particularly hereinafter set forth and claimed.

20 In the accompanying drawings, Figure 1 represents a front elevation of a shoe polishing machine embodying my invention, incased; Fig. 2 represents a rear view of the same, the outer casing and protruding parts being removed; Fig. 3 represents a detail plan view of the shifting gear and its frame; Fig. 4 represents a detail side elevation of section Y and rod W hereinafter described, the former being shown in elevation, the latter in cross section. Fig. 5 represents an end elevation of the entire machine incased; and Fig. 6 represents a horizontal section through Fig. 3, certain parts being shown in elevation.

25 A designates a long seat for the persons whose shoes are to be polished; B, a series of foot-rests below the same; C, a back to said seat; D, electric lamps behind the foot-rests and attached to sockets d in a space D' under said seat; E, end pieces of said seat at right angles to said back; G, a longitudinal slot in the front of the machine casing below said seat and foot rests; and H, a lower platform.

30 I, J and K designate drawers for loose articles such as the motor starter, extra brushes, blacking &c., arranged as convenient in different parts of the front of said casing.

35 A driving shaft L is mounted behind slot G on a frame M, preferably secured to the flooring or any fixed base normally within the casing of the seat and under the latter. An electric motor P, secured on the same base, drives the said shaft through belt O and pulleys O' O'', thereby rotating also any convenient number 40 of flexible brush-carrying shafts geared to said driving shaft and extending outward through said slot. We have illustrated in the accompanying drawings only one of said flexible shafts, marked R, but its duplication or multiplication at will is readily understood. The 45 gearing between these two shafts consists of a bevel friction wheel P' as hereinafter stated, feathered on

the driving shaft for adjustment along the latter and a corresponding friction pinion Q, turning with the said flexible shaft and mounted in a bracket T, having two inwardly extending arms which end in hubs t surrounding the elongated feathered hub or sleeve P' of wheel P. One half of each hub t is integral with the said bracket, the other half being bolted thereto through corresponding flanges t' of said hubs. Said sleeve has an annular shoulder P'' which forms a backing for 60 said wheel and may be considered as practically a part of it, though the wheel proper is non-metallic and preferably of vegetable fiber, affording a good friction surface and easily replaced when worn. Collars t' are fast on said sleeve in proximity to both ends of 65 the left hub t, and aid the shoulder P'' aforesaid and a peripheral enlargement of the right end of said sleeve in holding the hubs t in position and preventing their endwise slip thereon. The said sleeve is readily slipped along the driving shaft to any point where it 70 may be needed, the said gear wheel, bracket, pinion and flexible shaft moving with it, and the slot G allowing said flexible shaft to run straight out from the main shaft at any point to which it may thus be adjusted, so that the minimum length of flexible shafting 75 may be employed. The said bracket T is provided with a cylindrical recess T' in its inner face, receiving a corresponding integral cylindrical stem Q' of said friction pinion Q and allowing the latter at will to be drawn back out of contact with the wheel. Said 80 bracket has also a cylindrical rearward integral tubular bearing T'' centrally bored for the passage of a short inflexible shaft X, on which the pinion Q is fastened, so that the said pinion and this shaft move together 85 both axially and longitudinally, as though integral. 90

The outer end of shaft X is slotted or bifurcated at X' to receive the reduced inner end r of the coupling stem R' of flexible shaft R, these parts r and X' permitting independent longitudinal adjustment of shaft X and pinion Q without moving outwardly or inwardly the 95 flexible shaft R, although these shafts R and X turn together. Shaft X is also provided with a collar or annular shoulder X'', integral with it or fixed thereon. This is held between two opposite shoulders y and z of tubular sections Y Z which, with the said bracket, complete 100 the bearing casing of shaft X. Each of these sections has a rearward cylindrical recess concentric with said shaft, that of the inner section Y receiving the said bearing T'' of the bracket T; and the similar recess of section Z receiving a corresponding extension Y' of section Y. At this point a set screw Z' fastens the said sections Y and Z so that they must move together, both 105 rotatively and longitudinally. In said section Y is formed an oblique slot Y'' receiving a screw or stud Y''' (Fig. 3) of the fixed bearing T''. A handle U fixed to 110 section Z facilitates the turning of said sections together and such axial movement by the contact of the inclined

walls of the said slot with the said fixed stud moves the said sections Y Z outward or inward longitudinally according to the direction of motion of the handle. The shaft X of course participates in this endwise shifting 5 of the said sections by reason of the arrangement of the collar X² between shoulders y and z and in contact therewith.

An additional extension or tip Z⁴ is fastened by a screw Z⁵ on an outward extension Z³ of section Z and 10 has an enlargement Z⁶ of its central bore to receive the rear end of the flexible shaft R, said bore receiving and fitting the said coupling stem of said flexible shaft. This tip Z⁴ of the shaft casing turns with the sections Y Z in the above described axial movement for endwise 15 adjustment and also moves endwise with them during the same, but permits the shafts R and X to turn without impediment in said shaft casing. The section Z and tip Z⁴ protrude through the slot G in the front of the machine and the brush S may rest on platform H when 20 but of use or be applied from any direction, lightly or firmly, to any part of the shoe which is undergoing polishing and rotated to effect that result. Practically the parts Y, Z and Z³ constitute collectively an independently adjustable extension of bracket T, which is the 25 bearing of the flexible shaft and its friction pinion Q, their function being to provide for gearing or ungearing the latter at will. Of course if this function were dispensed with the bearing and casing might be simplified and my invention is not confined to the more convenient 30 construction shown.

The handle U is of course available to move the flexible shaft and intervening devices longitudinally of the shaft as well as for the connection and disconnection of such gearing.

35 W designates a fixed guide rod or bar parallel with the driving shaft L and fitting into a transverse groove V in the underside of section Y. This rod supports the outer part of the said section and the corresponding part of bracket T and by its engagement with the wall of said 40 groove prevents the said section from pushing out beyond the point indicated in the drawings. Such movement might jar the front of the casing injuriously.

Of course toothed gearing may be substituted for the 45 conoidal friction gearing shown, but it is objectionable by reason of its noise and on other grounds. Some other source of power may of course be substituted for the

electric motor above referred to; but it is the most convenient where electric connections may easily be made.

The especial construction of the foot-rests shown is not claimed in this application, being claimed as well 50 as more particularly set forth in my application No. 295,312 filed concurrently herewith.

It is not necessary that the short shaft X should be independent of the flexible shaft R in axial movement.

Having thus described my invention, what I claim 55 as new and desire to secure by Letters Patent is:

1. In a shoe brushing machine, the combination of a driving shaft with a flexible shaft, a brush carried by the latter, gearing between said shafts adapted to be shifted along said driving shaft, and a seat-supporting casing 60 slotted opposite said driving shaft to permit the direct outward extension of said flexible shaft from any point of the driving shaft to which it may be shifted.

2. In a shoe-brushing machine, the combination of a driving shaft with a flexible shaft, a brush carried by 65 the latter, a bracket providing a bearing for a short shaft attached to the flexible shaft, a wheel having its hub feathered on the main shaft and movable along the latter with said bracket, a pinion on said short shaft and driven by said wheel, the said short shaft means for connecting it to said flexible shaft and a seat supporting casing which incloses said main shaft and is provided with a horizontal slot in its front to permit the protrusion of 70 said short shaft and the shifting of said wheel and bracket along said main shaft substantially as set forth. 75

3. In a shoe brushing machine, the combination of a casing, a motor and driving shaft inclosed therein, gearing connecting these parts, a flexible brush-carrying shaft and bevel gearing rotatively connecting these shafts together and adjustable along the driving shaft, means, transversely grooved on the under side, for connecting said flexible shaft to an attachment of said driving shaft and a guide rod or bar fitting into the groove of said means for supporting the latter and preventing its outward movement, substantially as set forth. 80

4. In a shoe brushing machine, the combination of a driving shaft with a flexible shaft, a brush carried by the latter, gearing connecting the two shafts and adjustable along the driving shaft, a guide rod parallel with the said driving shaft and a supporting bracket for said flexible 90 shaft and a section Y extending forward from said bracket resting on the said guide rod and recessed on its under side to receive the same substantially as set forth.

In testimony whereof, I have signed my name to this specification in the presence of two subscribing witnesses. 95
